UNITED STATES PATENT OFFICE.

STEVE KARDOS, OF CLEVELAND, OHIO.

WINDOW-CLEANING DEVICE.

Application filed February 20, 1925. Serial No. 10,621.

To all whom it may concern:

Be it known that I, STEVE KARDOS, a citizen of the Republic of Hungary, residing at Cleveland, in the county of Cuyahoga and State of Ohio, have invented new and useful Improvements in Window-Cleaning Devices, of which the following is a specification.

This invention relates to a window seat, the general object of the invention being to provide means whereby windows can be easily cleaned or otherwise worked upon by a person sitting in the seat.

Another object of the invention is to make the device adjustable so that it can be used on buildings of various kinds.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view through a portion of a building showing the device in use.

Figure 2 is a front view of the device.

Figure 3 is a perspective view thereof.

Figure 4 is a section on line 4—4 of Figure 1.

In these views, 1 indicates a pair of bars, preferably formed of angle iron, and having their front ends bent downwardly at right angles, as shown at 1'. These ends are connected together by a board 2 and a seat board 3 is bolted to the other ends of the bars. A second seat board 4 is hinged to the board 3 by the hinges 5, this board engaging the horizontal flanges of the bars 1 when in lowered position. A back frame 6 is hinged to the board 3 by the hinges 7 and this frame is held in raised position by the braces 8, the lower ends of which are detachably connected with the bars 1 by the bolts 9. Braces 10 are hinged to the bars 1 by the hinges 11 and these braces have curved lower ends 12 for engaging the wall of a building, as shown in Figure 1. Links 13 are pivoted to the braces 10 and are adjustably connected with the bars 1 by

bolts 14 which may pass through any one of a plurality of holes 15 and 15' formed in the links and the bars so that the braces 10 can be adjustably connected with the bars 1 so that the device can be used with different kinds of buildings. In order to permit this adjustment the seat board 4 must be raised to permit access to the bolts 14, as shown in Figure 4.

As shown in Figure 1 the bars 1 are placed upon the window sill with the strip 2 engaging the inner part of the sill and with the curved ends of the braces 10 resting against the exterior wall of the building. Thus the device will be firmly supported and a person can sit upon the same and wash the window. When not in use the device can be folded so that it will occupy but little space.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A device of the class described including a pair of angle shaped bars arranged in parallel spaced relation with each other and each having one end bent at right angles to the body portion, a cross piece connecting the bent ends for engaging a window sill, a seat board fastened to the horizontal flanges of said bars, a second seat board hinged to the first board and resting upon the horizontal flanges of the angle bars, a back frame hingedly connected to the first seat board, brace members connecting the back frame to the bars, brace members hingedly connected to the bars at the ends thereof opposite the angular portions and having their free ends curved to engage a wall, links having their lower ends connected to the said last mentioned brace members and having their upper ends formed with a plurality of openings, the vertical flanges of the bars having openings therein and bolts adapted to be arranged in one of the openings of the links and bars whereby to adjustably connect the links to said bars.

In testimony whereof I affix my signature.

STEVE KARDOS.
